UNITED STATES PATENT OFFICE.

ELMER E. WELLS, OF GOLTRY, OKLAHOMA.

SILO-ROOF

1,107,002.

Specification of Letters Patent. Patented Aug. 11, 1914.

Application filed September 2, 1913. Serial No. 787,729.

To all whom it may concern:

Be it known that I, ELMER E. WELLS, a citizen of the United States, residing at Goltry, in the county of Alfalfa, and State of Oklahoma, have invented certain new and useful Improvements in Silo-Roofs; and I do hereby declare the following to be a full, clear, and exact description of the invention, such as will enable others skilled in the art to which it appertains to make and use the same.

This invention relates to silos, and more particularly to self supporting silo roofs.

One of the principal objects of my invention is to provide a silo roof having hinged sections so constructed and arranged as to be self supporting when the sections are in closed position.

Another object of the invention is to provide a silo roof having self supporting sections hinged at their central portions so that only a portion of the roof large enough to allow of the entrance of ensilage may be opened.

A further object of the invention is to provide a silo roof of the class described which will be simple, durable, efficient in operation and inexpensive to manufacture.

With these and other objects in view which will become apparent as the description proceeds the invention consists in the construction, combination and arrangement of parts hereinafter more fully described and claimed and illustrated in the accompanying drawings in which like characters of reference indicate like parts throughout the various figures of which.

Figure 1, represents a perspective view of a silo roof constructed according to my invention the same being shown in closed position. Fig. 2, represents a perspective view of the roof shown in open position. Fig. 3, represents a perspective view of a portion of the silo wall showing one of the hinge cleats secured thereon. Fig. 4, represents a vertical, longitudinal sectional view of the lower portion of one of the roof sections showing the manner of hinging it to the silo wall. Fig. 5, represents a perspective view of one of the roof sections. Fig. 6, represents a perspective view of a silo roof in open position, the roof sections being hinged at their central portions. Fig. 7, represents a detail perspective view of the portions of two adjacent roof sections showing the manner in which they are secured when in closed

position. Fig. 8, represents a vertical sectional view taken transversely of Fig. 7. Fig. 9, represents a vertical, longitudinal, sectional view through one of the centrally hinged roof sections a portion of the lower member being broken away and the hinged section being illustrated in closed position and, Fig. 10, represents a view similar to Fig. 9 the section being in open position.

The sections 5, of the roof illustrated in Fig. 1 comprise segments of a circle, and are hinged so that when in closed position the roof will be in the form of a cone and each section is provided on its outer edges with outwardly extending strips of angle iron 6, the opposing faces of the angle iron secured to adjacent roof sections adapted to lie against each other when the sections are closed so that when in closed position the sections will coat for supporting each other. The extreme outer end of the sections have their opposite edges slightly converged so that when the sections are in open position the edges of the outer end will clear each other, since the sections are pivoted along the line connecting the meeting points of the upper converging and lower converging edges of the sections.

The roof sections are provided with eye bolts 7, secured to the sections by means of washers 8, and nuts 9 and an eye bolt is secured near the opposite edges of each section and the adjacent eye bolts of adjacent roof sections are adapted to engage oppositely extending pins 10, secured in cleats 11, as shown in Fig. 3 said cleats comprising an outer portion 12, adapted to rest against the outer face of the silo wall, an upper horizontal portion 13, adapted to rest against the upper edge of the silo wall and an inner portion 14, adapted to rest against the inner face of the silo wall, said portions 14 and 12 being connected by bolt 15 which passes through the wall, and the lower end of portion 12 being also secured to the wall by means of the bolt 16. The cleats are positioned in spaced relation on the wall of the silo, a cleat occurring beneath the meeting edges of adjacent roof sections, the outer end of the sections extending beyond the cleats and beyond the outer faces of the silo wall as illustrated in Fig. 4. At spaced intervals along the outwardly extending angle-irons 6, pairs of openings 7, are provided, said openings 11 being arranged so that when the sections are in closed position the openings in one angle

iron will register with the openings in the adjacent angle iron, and through the lower openings of each adjacent pair is adapted to be passed and secured, a bolt 18 as illustrated in Fig. 8 thus securing the sections in closed position, said bolts adapted to be removed when the sections are to be opened, so that the latter may be swung outwardly on their pivots, it being understood however, that even when the bolts are removed the sections will support each other by reason of the angle irons of one section lying against the angle irons of adjacent sections. The upper openings of the pairs are adapted to receive hoops 19 when the sections are in open position as shown in Fig. 2, said hoops being formed of wire or other material, passed through the openings and having their ends secured in any desirable manner and said hoops occur in spaced relation and hold the sections in open position.

When it is desired to close the roof section 5 hoops 19 are removed and two of said sections are folded downwardly and bolted together through the openings 17 and by reason of the silo being circular these will be held in said downward position. The other of said sections may then be swung into closed position and the ends thereof will engage the ends of the section already closed and the side flanges 6 of the sections being in engagement with each other bolts may be passed through the opening 17 so as to secure the sections in the closed position, thus roofing the silo.

The silo illustrated is provided with a feed chute 20, of a width which is equal to the width of the greatest width of a roof section 21, and is capped by the movable member 27 as shown and is hinged to the top of the wall as are the other sections and is also hinged as at 22, to one of the adjacent roof sections, said hinges 22 being secured to the adjacent section by means of bolts, or rivets, and being secured to section 21 by means of removable screws and placed so that when the sections are to be opened, the hinges may be unfastened from section 21 so that said section and its adjacent section to which hinges 21 are secured may be swung outwardly on their pivots. Section 21 is provided with the hinges so that if it is so desired it may be opened while the remaining sections are closed, the bolts connecting said section with the section opposite to the section to which the hinges 22 are secured, having been previously removed and the bolts 9 by which it is secured to its eye bolts 7 having been removed so that it may be swung with the hinges 22 as pivots.

The form of section illustrated in Figs. 6, 9, 10 comprises an upper member 23 and a lower member 24 the latter being secured in any desirable manner, to the silo wall or being hinged thereto in a manner similar to

the roof sections 5 and the upper member 23 is hinged to member 24 by means of cleats 25 having oppositely extending pins similar to cleats 11, and eye bolts 26, said upper and lower portions provided with angle iron 6, 70 as are the sections 5. The members 23 are adapted to be swung outwardly when the silo is opened, the opening in the roof thus formed being adequate to receive the ensilage and said members are supported in open 75 position in the same manner as are the sections 5. The form of roof just described is intended to be used with silos of a larger diameter than usual, the form shown in Figs. 1 and 2 being desirable for use with 80 silos of medium size. The upper members 23 are provided with openings 17 said openings adapted to receive bolts and hoops in the manner disclosed in the description of the form of roof shown in Figs. 1 and 2. 85 The cleats 25 are adapted to be secured to the upper edges of lower portions 24 of the hinged roof sections, said portions forming in combination with the upper members 23 segments of a circle, it being noted however 90 that the extreme lower ends of upper members 23 are slightly converged to allow the members to swing outwardly.

Although I have described the preferred embodiment of my invention I may desire 95 to make such changes in the construction, combination, and arrangement of parts as do not depart from the spirit of the invention and the scope of the appended claims.

Having thus fully described my invention 100 what I claim as new and desire to secure by Letters Patent is:—

1. A self-supporting conical roof for silos, comprising segmental sections hinged at their larger end to the side wall of said silo, 105 angle irons secured adjacent the edges of said sections and being provided with perforations, bolts passed through the perforations of two of said sections for bolting the same together when closing the roof, and 110 said two sections forming a support for the remainder of said sections until said remaining sections are bolted together through said perforations.

2. A self-supporting conical roof for silos 115 adapted to open from the apex thereof comprising triangular sections having their larger ends secured to the side wall of the silo, angle irons secured to the longitudinal edges of said sections and being provided 120 with spaced perforations therein, means passed through said perforations for securing said sections together when in closed position, a plurality of hoops adapted to be received within said perforations for holding 125 said sections in an upward open position.

3. A self-supporting conical roof for silos adapted to open from the apex of said cone comprising a plurality of triangular sections hinged to the side wall of the silo, means for 130

holding said section in open position, means for holding said section in closed position, hinge members carried by one of said sections and adapted to be secured to the longitudinal edge of an adjacent section when said sections are in closed position whereby said adjacent section may be opened upon said first mentioned sections.

4. A conical roof for silos comprising sections forming a frustro-cone, sections pivoted to the upper edge of said first mentioned sections and adapted to extend in parallelism from said first mentioned sections to form the apex of said cone, and said

last mentioned sections being adapted to be 15 extended upwardly to provide an opening for the silo and means for retaining said last mentioned sections in an upward position to prevent the loss of ensilage when the silo is filled.

In testimony whereof I have signed my name to this specification in the presence of two subscribing witnesses.

ELMER E. WELLS.
